UNITED STATES PATENT OFFICE.

JOHN F. LOCKE, OF RYE, NEW HAMPSHIRE.

BRACKET FOR STAGES OR SCAFFOLDS.

SPECIFICATION forming part of Letters Patent No. 365,830, dated July 5, 1887.

Application filed November 27, 1886. Serial No. 220,633. (No model.)

To all whom it may concern:

Be it known that I, JOHN F. LOCKE, of Rye, county of Rockingham, State of New Hampshire, have made certain new and useful Improvements in Brackets for Stages or Scaffolds, of which the following is a specification, taken in connection with the drawings accompanying and forming a part hereof, in which—

Figure 1 is a side view of the bracket applied to the wall of a building, the wall and the securing-block of the bracket-fastening being in section. Fig. 2 is a detail of the bracket-pin detached. Figs. 3 and 4 are respectively a side and top view of the securing-block.

The object of my invention is the construction of a fastening by the use of which brackets such as carpenters use for supporting their staging or scaffolding in the erection of buildings may be more securely and easily fastened to the wall of the building, and the parts of which are less liable to be lost; and it consists in a pin adapted to be secured to the bracket so as to project from the vertical portion thereof, and having an enlarged head, and a slotted securing-block adapted to be passed over the head of the pin at one point and then to be moved on the pin, so as to bring the enlarged head thereof opposite the narrower part of the slot, thereby preventing the pin from leaving the block.

My invention is very simple, and will be readily understood from the following description and the accompanying drawings, throughout which like letters of reference indicate like parts.

A represents the wall of a building or the object to which the bracket is to be secured.

K is a bracket of common form, to which the pin B is secured in a suitable manner, preferably by bolting or screwing the flattened shank portions a to the horizontal portion of the bracket, and allowing the body of the pin to pass through a hole in the vertical portion of the bracket, as shown. The portion of the pin which projects from the bracket passes through the hole in the wall A to which the bracket is to be secured, and is provided with an enlarged head, C, by means of which the securing-block D is held in place on the pin.

The head C may be either of larger diameter than any other portion of the pin, or it

may be of equal diameter with the body b of the pin; and the part directly behind the head is flattened or cut away, as shown at d, Fig. 2, in order to be received in the narrow portion 55 of the slot f in the securing-block D.

The securing-block D is preferably of a wedge shape, being thicker at its upper end than at its lower end when in position, and is provided lengthwise with a slot, f, which is enlarged at 60 the lower or thin end of the block into a size sufficient to admit the head C of the pin. The slot f is of a size to admit the flat portion d of the pin, and to prevent the edge of the slot from wearing and render the block D stronger 65 and more durable. Its face is provided with a protecting-strip, E, secured thereto, against which the head C of the pin will bear when the bracket is in position on the building.

To secure the bracket in place, the pin is 70 thrust through the wall A and the block D is slipped over the head of the pin, the head passing through the enlarged portion of the slot in the block, and the block is then passed downwardly, wedging the block firmly between 75 the head of the pin and the wall, the narrow portion of the slot receiving the narrow part d of the pin. The wedge shape of the block enables the bracket to be secured firmly to different thicknesses, and the large bearing- 80 surface of the block against the wall prevents the bracket from tearing out, as sometimes happens with the brackets in common use when the rough boarding of the building, to which the bracket is usually secured, is rotten or 85 weak or in any way defective. The size and bearing-surface of the block D also clamp the bracket much more securely to the building than the small bearing-surface of the thumb-nut which is screwed onto the end of the 90 bracket-pin in brackets as now commonly constructed.

Although, as heretofore mentioned, a pin might be used having a round body, instead of the flat portion shown at d, provided the head 95 was enlarged, yet I deem the construction shown preferable, since the flat part d is received within the narrow portion of the slot f, and thus prevents the block from turning on the pin, otherwise there would be danger of 100 the block turning on the pin, then dropping down so as to bring the head of the pin oppo-

site the enlarged portion of the slot, and thus allowing the bracket to fall.

What I claim is—

1. The combination, with a bracket provided with a fastening-pin having an enlarged outer portion or head, of a wedge-shaped securing-block, D, having a slot of proper width to allow the said block to be movable longitudinally on the portion of the said pin adjacent to the said head, and the said slot being enlarged near the thinner end of the said block to permit the latter to be passed over the head of the said pin, substantially as set forth.

2. The combination, with the pin B, provided with means for securing it to the bracket 15 and having a head, C, of the slotted wedge-shaped block D, having the metallic protecting-strip E, secured to one face thereof, for the purposes and substantially as described and shown.

JOHN F. LOCKE.
